UNITED STATES PATENT OFFICE

139,006

DESIGN FOR A TURRET DIRECTION INDICATOR

Bert F. Baker, Riverdale, Md.

Application December 30, 1943, Serial No. 112,120

Term of patent 3½ years

(Cl. D52—1)

To all whom it may concern:

Be it known that I, Bert F. Baker, a citizen of the United States, residing at Riverdale, in the county of Prince Georges and State of Maryland, have invented a new, original, and ornamental Design for Turret Direction Indicator, of which the following is a specification, reference being had to the accompanying drawing, forming part thereof, in which:

Figure 1 is a plan view of the turret direction indicator showing my new design, and

Figure 2 is a side elevational view thereof.

I claim:

The ornamental design for a turret direction indicator, as shown.

BERT F. BAKER.
